UNITED STATES PATENT OFFICE.

HARRY WARD, OF KOKOMO, INDIANA, ASSIGNOR TO THE KOKOMO WIRE AND NAIL COMPANY, OF SAME PLACE.

DESIGN FOR A WIRE FENCE.

SPECIFICATION forming part of Design No. 33,509, dated November 6, 1900.

Application filed October 8, 1900. Serial No. 32,449. Term of patent 14 years.

To all whom it may concern:

Be it known that I, HARRY WARD, a citizen of the United States, residing at Kokomo, in the county of Howard and State of Indiana, have invented and produced a new and useful Design for Wire Fences, of which the following is a specification.

In the drawing I have shown a side elevation of a wire fence presenting my design.

As shown in the drawing, the leading or important feature of my design consists in a fence having horizontal or strand wires A, B, C, D, E, F, G, H, I, and J, running longitudinally through the fence, and the stay-wires K and the woof-wires L, arranged in connection with the horizontal or strand wires, as shown. The stay-wires K are arranged in a vertical position and engaged with or wrapped around the upper horizontal wires A, B, C, D, and E, and the woof-wires L are engaged with or wrapped around the horizontal or strand wires E, F, G, H, I, and J, so as to

produce therewith what is known as or generally termed a "diamond" mesh. The stay-wires engage the upper horizontal wires at right angles, and the woof-wires run diagonally back and forth across the spaces between the lower horizontal wires, so as to produce the diamond mesh. A fence constructed of horizontal or strand wires and vertical stay-wires in its upper portion and diagonally-arranged woof-wires in its lower portion presents the appearance of a combined diamond-mesh and stay-wire fence, as shown in the drawing.

What I regard as new, and desire to secure by Letters Patent, is—

The design for a wire fence herein shown and described.

HARRY WARD.
